(57) **CLAIM**

The ornamental design for a foot for a medical mobility device, as shown and described.

DESCRIPTION

FIG. 1 is a top perspective view of a foot for a medical mobility device in accordance with the present design;

FIG. 2 is a plan view thereof;

FIG. 3 is a top view thereof; and,

FIG. 4 is a bottom view thereof.

The broken lines shown in the drawings illustrate portions of the foot for a medical mobility device that form no part of the claimed design.
